UNITED STATES PATENT OFFICE

CHARLES H. LAY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed March 24, 1931. Serial No. 524,779.

My invention relates to railway traffic controlling apparatus, and particularly to apparatus for the automatic control of railway signals and/or train stopping devices. One feature of my invention is the provision of novel and improved means for giving more than three restrictive indications in the rear of a train.

I will describe one form of apparatus embodying my invention, and will then point out the novel features thereof in claims.

In the accompanying drawings, Figs. 1^a and 1^b, when placed end to end with Fig. 1^a on the left, constitute a diagrammatic view showing one form of apparatus embodying my invention.

Referring to the drawings, the reference character E designates a railway track along which traffic normally moves in the direction indicated by the arrow. The rails of this track are divided by the usual insulated joints to form a series of track sections 1—2, 2—3, etc. Each section is provided with a track circuit, and these track circuits, as here shown, are of the center-fed type, comprising a battery 7 connected across the rails at an intermediate point in the section, and two track relays T and AT connected across the rails at the entrance and exit ends respectively.

Each section is provided with two polarized relays A and B, and these relays are provided with slow-releasing repeater relays AS and BS, respectively. Also associated with each section is an approach lighting relay L, and a battery C.

Referring particularly to repeater relay 3BS, this relay is provided with a circuit which passes from the plus terminal of battery C3, through front contact 25 of relay 3B, and the winding of relay 3BS to the minus terminal of battery C3. It follows that relay 3BS is energized when relay 3B is energized in either direction, but is deenergized when relay 3B is deenergized. Each relay S is controlled in a similar manner by the associated polarized relay A or B.

Each two adjoining sections are provided with a line circuit which includes, in series, relay A for the forward section and relay B for

the rear section, and current of normal or reverse polarity is supplied to such circuit according as the repeater relay BS for the section next in advance of the forward section is closed or open. Referring to sections 3—4 and 4—5, for example, the line circuit for these sections passes from the plus terminal of battery C3, through the front point of contact 13 of relay 3BS, front contact 14 of track relay 4AT, winding of approach lighting relay 3L, front contact 15 of relay 4T, winding of relay 4A, front point of contact 16 of track relay 5AT, front point of contact 17 of track relay 5T, winding of relay 5B, front point of contact 18 of track relay 5T, front point of contact 19 of relay 5AT, front point of contact 20 of relay 4T, front point of contact 21 of relay 4AT, and the front point of contact 22 of relay 3BS, to the minus terminal of battery C3. Relay 3BS being closed, the current which is supplied to this circuit is of normal polarity, so that relay 3L is energized when relays 4A and 5B are both energized in the normal direction. The polar contacts of the two latter relays are therefore swung to the left. When relay 3BS is open, and the line circuit just traced is closed at all other points, current of reverse polarity is supplied thereto, because of the fact that contacts 13 and 22 of relay 3BS function as a pole-changer. Relays 4A and 5B will then be energized in the reverse direction, so that their polar contacts will be swung to the right.

Each section is provided with a signal S, comprising two groups of lamps. The upper group is made up of a green lamp GA, a yellow lamp YA, and a red lamp RA. The lower group is similarly made up of a green lamp GB, a yellow lamp YB, and a red lamp RB. Referring particularly to signal S3, when relays 3A and 3B are both energized in the reverse direction, as shown in the drawings, and when approach lighting relay 3L is deenergized, the yellow lamp YA of the upper group will be lighted, the circuit being from the plus terminal of a battery C3, through back contact 8 of relay 3L, front point of contact 11 of relay 3AS, polar contact 12 of relay 3A in the reverse position, 106

and lamp YA of signal S3 to the minus terminal of battery C3. The yellow lamp YB of the lower group in this signal will also be lighted, the circuit being from the plus terminal of battery C3, through back contact 8 of relay 3L, front point of contact 9 of relay 3BS, polar contact 10 of relay 3B in the reverse position, and lamp YB to the minus terminal of battery C3. When relay 3A becomes energized in the normal direction, lamp GA of signal S3 will become lighted by virtue of a circuit which will be obvious from the drawings. Similarly, when relay 3B becomes energized in the normal direction, lamp GB will become lighted by virtue of a circuit which will be obvious from the drawings. When relay 3AS opens in response to deenergization of relay 3A, red lamp RA will become lighted, the circuit being from the plus terminal of battery C3, through back contact 8 of relay 3L, back point of contact 11 of relay 3AS, and lamp RA to the minus terminal of battery C3. Similarly, when relay 3BS opens, red lamp RB will become lighted by virtue of a circuit which will be obvious without detailed explanation. It is understood, of course, that all lamps of signal S3 will be extinguished except when the approach lighting relay 3L is deenergized. The controlling circuits for each of the signals are similar to those which have been traced for signal S3.

As shown in the drawings, an automatic train stopping device D is provided for each track section, and this device is provided with a clearing circuit which is closed when and only when both of the polarized relays A and B for the associated section are energized in the normal direction. Considering the device D3 for section 2-3, for example, the clearing circuit for this device is from one terminal of its operating winding, through polar contact 13 of relay 3B in the normal position, front contact 26 of the same relay, front neutral contact 27 of relay 3A, and polar contact 14 of relay 3A in the normal position, to the other terminal of the operating winding for the device D3.

As shown in the drawings, the section to the left of point 1, is occupied by a train F, so that track relay 1T is open. The circuits for relays 1A and 1B are therefore open, so that relays 1AS and 1BS are deenergized. If approach lighting relay 1L were deenergized, due to the presence of a train in section 1-2, the red lamps RA and RB of signal S1 would both be lighted. Relay 2B is deenergized because its circuit is open at track relay 1T. Relay 1BS being open, relays 2A and 3B are energized in the reverse direction. Relay 2B being open, relay 2BS is open, so that relays 3A and 4B are energized in the reverse direction. Relay 3BS being closed, relays 4A and 5B are energized in normal direction. Relay 5A is energized in

the normal direction because relay 4BS is closed.

At point 2, then, relay 2A is energized in the reverse direction, so that lamp YA of signal S2 is lighted; and relay 2B is deenergized, so that relay 2BS is, likewise, deenergized, and the lamp RB of signal S2 is lighted. (It is assumed at this point, and at all similar points hereinafter, that the approach lighting relay for each signal is deenergized due to the train approaching such signal.) This signal then indicates that the second section in advance is occupied. At point 3, both relays 3A and 3B are energized in the reverse direction, so that the yellow lamps YA and YB of signal S3 are both lighted. Signal S3 indicates, therefore, that the third section in advance is occupied by a train. Relay 4A being energized in the normal direction, lamp GA of signal S4 is lighted, and relay 4B being energized in the reverse direction, lamp YB of this signal is also lighted. Signal S4 then indicates that the fourth section in advance is occupied by a train. Relays 5A and 5B are both energized in the normal direction. It follows that both of the green lamps of signal S5 are lighted, so that this signal indicates that the four blocks in advance are unoccupied.

When a train moving toward the left enters section 4-5, it will open track relay 5T, and the contacts 17 and 18 of this relay will then exclude relay 5B from its circuit and will close an auxiliary path for relay 4A, which path includes a resistance 24 to take the place of relay 5B. It follows that relay 4A will remain energized. Similarly, when the train advances into the section to the point at which track relay 5AT will open, contacts 16 and 19 of this relay will close another branch for the line circuit of relays 4A and 5B, which branch includes a resistance 23, with the result that relay 4A will still remain energized. Of course, the opening of relay 5T will open the circuit for relay 5A, and the opening of relay 5AT will again open the circuit for relay 5A at another point. The operation of the apparatus during the progress of the train through the succeeding sections shown in the drawings, will be obvious from the foregoing without detailed explanation.

The train stopping devices D may, of course, be omitted, if desired, and the same thing is true of the approach lighting relays. Furthermore, if approach lighting of the signals is desired, it may be accomplished in any other suitable manner.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway track divided into sections, two polarized relays A and B for each section, means operating according as relay B for each section is energized or deenergized to supply current of normal or reverse polarity to relay A for the section next in the rear and to relay B for the second section in the rear, track circuits for the sections including track relays for the control of said polarized relays, and traffic governing means for the sections controlled by said polarized relays. 5 70
- 10 2. In combination, a railway track divided into sections, two polarized relays A and B for each section, a line circuit for each two adjacent sections including in series relay A for the forward section and relay B for the rear section, means for supplying each of said circuits with current of normal or reverse polarity according as relay B for the section next in advance of such forward section is energized or deenergized, track circuits for the 20 sections including track relays for the control of said line circuits, and traffic governing means for the sections controlled by said polarized relays. 75
- 25 3. In combination, a railway track divided into sections, two polarized relays A and B for each section, a slow releasing repeater relay for each relay B, means for controlling each repeater relay by a neutral front contact of the associated relay B, means operating according as the repeater relay for each section is energized or deenergized to supply current of normal or reverse polarity to relay A for the section next in the rear and to relay B for the second section in the rear, track 30 80
- 40 circuits for said sections including track relays for the control of said polarized relays, and traffic governing means for the sections controlled by said polarized relays and repeater relays. 85
- 45 4. In combination, a railway track divided into sections, two polarized relays A and B for each section, a line circuit for each two adjacent sections including in series relay A for the forward section and relay B for the 40 90
- 50 rear section, means for supplying each of said circuits with current of normal or reverse polarity according as relay B for the section next in advance of such forward section is energized or deenergized, a track circuit for each section including a track relay having front contacts included in the two line circuits of the section, a shunt around the B relay for each section including a back contact of the track relay for such section, 55 100
- 60 and signals for the sections controlled by said polarized relays. 105
5. In combination, a railway track divided into sections, two polarized relays A and B for each section, a line circuit for each two adjacent sections including in series relay A 65 110
- 115
- 120
- 125
- 130
- for the forward section and relay B for the rear section, means for supplying each of said circuits with current of normal or reverse polarity according as relay B for the section next in advance of such forward section is energized or deenergized, means operating when any one section is occupied by a train to open the line circuits including both relays A and B for such section and to close a branch path for the circuit including relay A of the section next in advance, and traffic governing means for the sections controlled by said polarized relays.
6. In combination, a railway track divided into sections, two polarized relays A and B for each section, a line circuit for each two adjacent sections including in series relay A for the forward section and relay B for the rear section as well as an approach lighting relay for the section next in advance of such forward section, means for supplying each of said circuits with current of normal or reverse polarity according as relay B for such section in advance of the forward section is energized or deenergized, track circuits for the sections for the control of said line circuits, and signals for said sections controlled by said polarized and approach lighting relays. 95
7. In combination, a railway track divided into sections, two polarized relays A and B for each section, means operating according as relay B for each section is energized or deenergized to supply current of normal or reverse polarity to relay A for the section next in the rear and to relay B for the second section in the rear, track circuits for the sections including track relays for the control of said polarized relays, and a train stopping device for each section, and a clearing circuit for each device closed if and only if both relays A and B for the associated section are energized in normal direction. 100
- In testimony whereof I affix my signature.
- CHARLES H. LAY. 110
